UNITED STATES PATENT OFFICE.

JOSEPH C. HAMM, OF GREENVILLE, NEW JERSEY.

DESIGN FOR A WINDOW-SHADE.

SPECIFICATION forming part of Design No. 12,354, dated July 12, 1881.

Application filed May 21, 1881. Term of patent 3½ years.

To all whom it may concern:

Be it known that I, JOSEPH C. HAMM, a citizen of the United States, residing at Greenville, in the county of Hudson and State of New Jersey, have invented a new and original 5 Design for Window-Shades, of which the following is a specification.

The drawing represents a front view of my design.
10 In this drawing, the letter A designates a pond; B, water-lilies; C, a swamp-lily; and D, a cat-tail, all being plants growing in water or swamps; and E E E are butterflies of various descriptions. Below bottom of the pond A is 15 a border, H, composed of two top lines, a b, a row of escutcheons, c d, two bottom lines, e f, and arcs g h, the arcs g terminating in circles i, and arcs h in leaves j. On the top of the main picture is a border, I, composed of 20 two bottom lines, k l, leaves m n, supported by the line l, and Gothic arcs v, supported by circles p, which rest upon the lines l. The

spaces between the arcs are ornamented by leaves q r.

What I claim as new, and desire to secure to 25 Letters Patent, is—

1. The design for a shade, consisting of a pond, A, water-lilies B, and plants C D, as shown and described.

2. The design for a shade, consisting of a 30 pond, A, water-lilies B, plants C D, and butterflies E, substantially as shown and described.

3. The design for a shade, consisting of a pond, A, water-lilies B, plants C D, butterflies E, and borders H I, substantially as shown 35 and described.

In testimony whereof I have hereunto set my hand and seal in the presence of two subscribing witnesses.

JOSEPH C. HAMM. [L. S.]
